(57) **CLAIM**

The ornamental design for a display device assembly with touchscreen and camera, as shown and described.

DESCRIPTION

FIG. 1 is a front, right perspective view of a display device assembly with touchscreen and camera showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front elevation view of the display device assembly with touchscreen and camera of FIG. 1 shown in alternate state with the camera in a retracted position; and, FIG. 9 is a rear elevation view thereof.

The broken lines depict portions of the display device assembly with touchscreen and camera that form no part of the claimed design.

1 Claim, 9 Drawing Sheets
